US00D835648S

(12) **United States Design Patent** (10) Patent No.: **US D835,648 S**
 Begin et al. (45) Date of Patent: **** Dec. 11, 2018**

(54) **DISPLAY SCREEN OR PORTION THEREOF
WITH A GRAPHICAL USER INTERFACE
FOR A THERAPY DEVICE**

(71) Applicant: **Smith & Nephew, Inc.**, Memphis, TN (US)

(72) Inventors: **Miles Begin**, New York, NY (US); **Ethan R. Bliss**, New York, NY (US); **Carrie Lee Childress**, Dallas, TX (US); **Giacomo F. Ciminello**, Cincinnati, OH (US); **William W. Gregory**, Gainesville, FL (US); **Kathryn Ann Leigh**, Saint Petersburg, FL (US); **Ke Li**, East Islip, NY (US); **Chelsea F. McLemore**, Long Island City, NY (US); **Benjamin S. CLAIM

The ornamental design for a display screen or portion thereof with a graphical user interface for a therapy device, as shown and described.

DESCRIPTION

FIG. 1 is a front view of a display screen or portion thereof with a graphical user interface for a therapy device, showing a first embodiment thereof; and,

FIG. 2 is a second embodiment thereof.

The outermost broken line showing the display screen or portion thereof defines the bounds of the claimed design and forms no part thereof. The remaining broken lines show portions of the graphical user interface. No subject matter depicted in any of the aforementioned broken lines forms part of the claimed design.
